UNITED STATES PATENT OFFICE.

HARRY E. SQUIRE, OF OAKLAND, CALIFORNIA.

COMPOSITE WALL AND METHOD OF CONSTRUCTING SAME.

Application filed June 12, 1924. Serial No. 719,468.

To all whom it may concern:

Be it known that I, HARRY E. SQUIRE, a citizen of the United States, and a resident of Oakland, in the county of Alameda, State of California, have invented a certain new and useful Composite Wall and Method of Constructing Same, of which the following is a specification:

The invention relates to walls and bulkheads built up of slabs or wall sections commonly known as sheet pile or pile and slab walls and particularly to that type of wall or bulkhead in which concrete slabs are employed in conjunction with driven piles.

An object of the invention is to provide a method of constructing such walls and bulkheads in a manner to reduce the cost thereof.

Another object of the invention is to provide a wall or bulkhead of the type involved, having a simplified and improved construction.

Walls and bulkheads of the type to which this invention relates have been constructed heretofore by driving the requisite number of piles, either wood or pre-cast concrete, at spaced intervals and then either casting slabs of concrete in place between adjoining piles, or by fitting pre-cast slabs of concrete in place with their ends or sides engaging adjoining piles in a manner to close the spaces between the piles. Difficulty has heretofore been encountered in casting the wall sections in place, because of the expense of such a process and the usually poor grade of concrete obtained by so doing, when the wall is built on submerged land as is usually the case. Similarly, in filling the spaces between the piles with pre-cast wall sections, difficulty has been encountered in producing

close engagement between the wall sections and the piles, due to the fact that piles, under practical working conditions, cannot be driven with the necessary accuracy to permit such engagement. Piles after being driven are usually out of vertical alignment and often turn upon themselves so that a pre-cast slab or wall section cannot be made to fit adjoining piles without leaving open spaces between the wall section and piles and consequently subjecting the slab to undesirable strains and stresses. Moreover, the open spaces tend to defeat the purpose of the wall which is usually to retain a fill which is readily washed out by the action of water and waves.

In my invention, the difficulties mentioned above are overcome by providing adjustable abutment members for the piles, fixing said abutment members in accurate position relatively to said piles to receive the wall sections and then placing said wall sections in position with their ends engaging the abutment members. In this manner the inequalities in the position of the piles are remedied by the adjustment of the abutment members. Firm and accurate abutments are provided for the wall sections and a wall as free from openings as is required in practice is produced.

The invention possesses other advantageous features, some of which with the foregoing will be set forth at length in the following description, where I shall outline in full the process of my invention and those forms of the apparatus for carrying out the process which I have selected for illustration in the drawings accompanying and forming part of the present specification. In said drawings I have shown two forms of apparatus but it is to be understood that I do not limit myself to such forms, since the invention as set forth in the claims may be embodied in a plurality of forms.

Referring to the drawings:

Figure 1 is an elevation of a wall embodying one form of the invention.

Figure 2 is a cross-sectional view on line A—A Figure 1.

Figure 3 is a cross-sectional view on line B—B of a part of the wall shown in Figure 2.

Figure 4 is a cross-sectional view of a wall embodying another form of the invention.

Figure 5 is a cross-sectional view of a wall embodying another form of the invention.

Walls of the type here involved are usually constructed over submerged land indicated at 10 in Figure 2. In carrying out the invention piles 11 are driven in place along the line of the proposed wall as nearly in accurate vertical alignment as possible but in practice these piles are necessarily found in irregular position as indicated in Figures 1, 3, 4 and 5. Pre-cast abutment members 12, having a central aperture 13, considerably larger in diameter than the piles 11, are placed around said piles, which then serve as abutment supports. By reason of the size of aperture 13, abutment members

12 can readily be adjusted about the piles or abutment supports 11 in a manner to bring them into accurate alinement and position, their bearing faces 14 being brought into proper position by twisting the abutment members about their respective supports 11. The abutment members 12 are then securely fastened in position on the supports 11 in any suitable manner, such as by placing filling material, such as grouting 15, between the abutment supports 11 and the interior of the abutment members as here shown. Wall sections 16, made of pre-cast slabs of concrete, or of stone or other material are then placed in position between adjacent abutment members 12 with the ends of said slabs engaging the bearing faces 14 of said abutment members. By reason of the accurate alinement and position of abutment members 12, obtained by the method above described, the engagement of said wall section and abutment members is quite accurate and provides a full bearing surface for the ends of wall sections 16, thus preventing undesirable strains and stresses on said sections and also providing a tight joint. In the form of the invention shown in Figures 3 and 5, the abutment members 12 are disposed with their bearing surfaces at an angle to the line of the wall, thus providing abutments capable of accommodating minor inequalities in size in wall sections 16. As shown in Figures 3 and 5, said wall sections are held in place by bolts 17 extending through spacing blocks 18 and clamps 19 as shown in Figure 3 or a second wall section 20, as shown in Figure 5.

In the form of the invention shown in Figure 4, the wall section 16 is held in place by bolts 21 carried by abutment members 12 and extending through space blocks 22 and clamping pieces 23. In practice it is found, however, that any temporary means of holding wall sections 16 in place may be employed, since said sections are automatically held in place by the filling material as shown at 24, Figure 2, which is usually retained by such walls.

After the wall sections are in place I prefer to fill the spaces 25 between the abutment members 12 and the wall sections 16 with grouting material to make a permanent joint. Where pre-cast slabs are employed as wall sections, it is desirable to drive them in place and during this operation the clamp 19 and clamping pieces 23 serve as guides to engage the abutment members 12 and direct the driven wall sections into proper position. The same function is performed by slab 20 in the form of the invention shown in Figure 5.

After wall sections 16 are securely in place, the entire wall may be bound together into a unitary structure by casting along the top thereof a concrete member or superstructure

26, having suitable reinforcing members 27 therein. The tops of slabs 16, abutment members 12 and abutment supports 11 are thus all bound into a single rigid structure.

While the sequence in the steps of the method hereinabove described is the preferred way of carrying out the invention, it is also possible to practice said invention by first placing abutment members 12 temporarily in position and then placing wall sections 16 between the adjacent abutment members with their ends engaging bearing faces 14 on such members. The abutment members 12 can then be adjusted into accurate position together with the wall sections 16 and the abutment members 12 then secured in position by placing filling material, such as grouting 15, between the abutment supports 11 and the interior of the abutment members 12.

I claim:

1. The method of constructing a wall which consists in securing an abutment support in position, placing an abutment member in adjustable relation with said abutment support, adjusting the position of said abutment member relative to said abutment support to a position where one face of said abutment will engage an end portion of a wall member, and then securing said abutment member in the latter position.

2. The method of constructing a wall which consists in positioning an abutment support, placing a hollow abutment member about said support, adjusting the position of said abutment member so that it is positioned for accurate engagement with a wall member and fixing said abutment member in said latter position relatively to said abutment support.

3. The method of constructing a wall which consists in positioning an abutment support, placing a hollow abutment member about said support, adjusting said abutment member to a position where it can accurately engage with a wall member, and then fixing said abutment member in position relative to said abutment support, by filling the space between said abutment support and said abutment member.

4. The method of constructing a wall which consists of positioning a plurality of abutment supports, placing an adjustable abutment member in engagement with each support, adjusting said abutment members relative to said support to a position where they can accurately engage with wall members, securing said abutment members in said position in fixed relation to said abutment supports, and placing wall members in engagement with adjoining abutment members.

5. The method of constructing a wall which consists in driving a plurality of piles, placing a hollow abutment member

about each of said piles, positioning said abutment members for engagement with wall members, fixing the position of said abutment members by placing filling material between said piles and the interior of said abutment members and then arranging wall members with their sides engaging adjoining abutment members.

6. The method of constructing a concrete wall which consists in driving a plurality of piles, placing a hollow concrete abutment member about each of said piles, positioning said abutment members for engagement with concrete wall members, placing said wall members with their sides engaging adjoining abutment members and casting a concrete superstructure along the upper ends of said abutment members and wall members.

20 7. The method of constructing a wall which consists in positioning a plurality of abutment supports, placing abutment members in adjustable engagement with said supports, placing wall members in engagement with adjoining abutment members, adjusting said abutment members relatively to said supports and then securing said abutment members in adjusted position.

8. The method of constructing a wall which consists in driving a plurality of piles, placing hollow abutment members about each of said piles, temporarily positioning said abutment members for engagement with wall members, arranging wall members with their sides engaging adjoining abutment members, adjusting the position of said abutment members relatively to said abutment piles and fixing the position of said abutment members by placing filling material between said piles and the interior wall of said abutment members,

40 9. The method of constructing a wall which consists in driving a plurality of piles, placing the hollow abutment members about each of said piles, temporarily positioning said abutment members for engagement with wall members, arranging wall

members with their sides engaging adjoining abutment members, adjusting the position of said abutment members relatively to said abutment supports, fixing the position of said abutment members by placing filling material between said piles and the interior wall of said buttress member and casting a concrete superstructure along the upper ends of said abutment members and wall members.

10. The method of constructing a wall which consists of positioning at least two abutment supports, positioning a single integral concrete abutment member over each support in such a manner that its position may be shifted a certain amount laterally, and placing a single concrete slab between said abutment members with its end portions engaging the same.

11. The method of constructing a wall which consists of positioning at least two abutment supports, positioning a hollow abutment member over each support in such a manner that its position may be shifted laterally a certain amount, rearranging each of said abutment members in such a position that they can engage with the end portions of a wall member of certain predetermined dimensions, and then fixing the abutment members in said latter position.

12. The method of constructing a wall which consists in driving a plurality of piles, placing hollow abutment members about each of said piles, temporarily positioning said abutment members for engagement with wall members, arranging wall members with their end portions engaging adjoining abutment members, adjusting the position of said abutment members relatively to said piles and fixing the position of said abutment members by placing filling material between said piles and the interior wall of said abutment members.

45 In testimony whereof, I have hereunto set my hand.

HARRY E. SQUIRE.
